Attorney

UNITED STATES PATENT OFFICE

MALCOLM McDONALD, OF ORENCO, OREGON

CARD INDEX AND FILE

Application filed August 31, 1927. Serial No. 216,616.

This application relates to my application in the United States Patent Office, filed April 15, 1926, Patent No. 1,649,244, Nov. 15, 1927, upon a Card index and file, and my present 5 application relates to two applications for patent filed concurrently herewith, upon a Card index and file, Ser. Nos. 216,214 and 216,615.

The primary object of my present invention 10 is to provide simple and efficient means for the maintaining of card indexes and the like.

A further object of my invention consists in providing a supporting yoke for the card holder disposed independent of the yoke to be 15 received within the guideway of the tray and gives a greater freedom of movement and a maximum of spaced relationship for inspection between the card and the adjacent card placed thereby.

20 With these and incidental objects in view, the invention consists in certain novel features of construction and combination of parts, the essential elements of which are set forth in the appended claims, and a preferred 25 form of embodiment of which is hereinafter shown with reference to the drawings which accompany and form a part of this specification.

In the drawings:

30 Fig. 1 is a fragmentary top plan view of the tray with the cards supported therein.

Fig. 2 is a fragmentary cross-sectional view, taken on line 2—2 of Fig. 1, looking in the direction indicated.

35 Fig. 3 is a fragmentary top plan view of the card holder and yokes and of the tray with which the same are associated.

Like reference characters refer to like parts throughout the several views.

40 1 is the card tray having guideway 18 disposed lengthwise thereof. In a preferred form of embodiment of the invention the yoke is shown at 17 in Fig. 2, and is formed about a central guideway 18, and has oppositely disposed upturned bosses 19 and 20 through 45 which the ends 21 and 22 of the card holder 23 may be made to pass. A central notch 15 is provided in the card holder 23 with which the indicator mark 16 in each card is made 50 to register to insure the positioning of the

cards in uniform spacing and alignment. The yoke 17 should be made of material having a substantial amount of springiness therein to permit of the passage of the ends 21 and 22 of the card holder 23 therethrough and freedom should be provided in the bosses 19 and 20 to permit of a free turning of the card holder 23 within the openings disposed in said bosses. 55

In the construction of the bosses of the 60 yokes, as illustrated in Fig. 3, the boss is formed by the upturning of flanges 24 and 25 to form an engaging socket, into which the card holder is made to engage. This form of construction may be used and the yoke made 65 of sheet stock, without the swaging or upsetting of the ends, and the central portion 26 should be so made as to permit of a snap engagement with the central guideway 18, thus permitting the removal of a yoke with 70 its card from the index or the insertion of the same after a card has been placed therein.

While the form of mechanism herein shown and described is admirably adapted to fulfill the objects primarily stated, it is to be understood that it is not intended to confine the 75 invention to the one form of embodiment herein shown and described, as it is susceptible of embodiment in various forms, all coming within the scope of the claims which 80 follow:

What I claim is:

1. In a device of the class described, a card index tray, a central guideway disposed longitudinally of the card index tray, said guideway 85 being disposed upon the upper surface of the bottom of the card tray and being rounded in form, a series of slidable yoke elements associated with the guideway and adapted to engagement and disengagement therefrom by being pressed into place relative to the guideway, the yoke elements having upturned bosses at each end and journal bearings disposed therein, and a card holder journaled within said bearings. 90

2. In a device of the class described, a card index tray, a central guideway, disposed longitudinally of the upper side of the bottom of the card index tray and rounded in form in cross section, a series of slidable yoke elements 95 100

associated with the guideway and adapted to a snap engagement and disengagement with the guideway, horizontal bearings disposed at either end of the yoke elements and a card holder journaled within the bearings of each yoke.

3. In a device of the class described, a card index tray, a guideway, rounded in cross section associated with the upper side of the bottom of the card tray, a multiple of yokes adapted to a snap engagement and disengagement with the guideway associated therewith, a series of horizontal bearings associated with either end of the yoke and formed by upturning ears formed of the yoke stock, and card holders having notches formed centrally of their edges journaled within the bearings of the yokes, and a card having an indicator mark formed central the lower side of its ends placed between the oppositely disposed surfaces of the card holder.

MALCOLM McDONALD.
